DINNER PLATE

Eva Zeisel, South Mountain Road, New City, N.Y.

Filed Feb. 3, 1964, Ser. No. 78,495

Term of patent 7 years

(Cl. D44—15)

FIG. 1 is a top view of the dinner plate, showing my new design;

FIG. 2 is a bottom view of the same;

FIG. 3 is a side view of the plate; and

FIG. 4 is a partial section view of the plate.

I claim:

The ornamental design for a dinner plate, as shown.
